(57) **CLAIM**

(21) Appl. No.: **29/170,375**

I claim the ornamental design for a combined portable compressor unit and battery, as shown and described.

(22) Filed: **Nov. 5, 2002**

DESCRIPTION

(51) LOC (7) Cl. **15-02**

FIG. 1 is a front elevation view of the combined portable compressor unit and battery in accordance with an embodiment of the present invention;

(52) U.S. Cl. **D15/9**

FIG. 2 is a rear elevation view thereof;

(58) Field of Search D15/7-9.1; 417/410.4,
417/359, 415, 410.3, 534, 215, 222.1, 269;
D23/324, 354, 163, 363; 418/259

FIG. 3 is a left side elevation view thereof;

(56) **References Cited**

FIG. 4 is a right side elevation view thereof;
